UNITED STATES PATENT OFFICE

ELMER N. JOHA, OF WAUWATOSA, WISCONSIN, ASSIGNOR TO RELIABLE KNITTING WORKS, OF MILWAUKEE, WISCONSIN, A CORPORATION OF WISCONSIN

DESIGN FOR A KNITTED HAT

Application filed May 9, 1931. Serial No. 39,799. Term of patent 7 years.

To all whom it may concern:

Be it known that I, ELMER N. JOHA, a citizen of the United States, residing at Wauwatosa, in the county of Milwaukee and State of Wisconsin, have invented a new, original, and ornamental Design for a Knitted Hat, of which the following is a specification, reference being had to the accompanying drawings, forming part thereof.

In the drawings:

Figure 1 is a plan view of the hat as exposed for sale, the fragmentary showing of knitted fabric being continued throughout the entire hat in practice.

Figure 2 illustrates the same as it appears

in use showing the hat as being made of knitted fabric.

The dominant features of my design are the hat made of a knitted fabric having a tight, form-fitting crown of soft and flexible weave; a brim of flexible knitted material having sufficient stiffness to cause it to stand away from the face of the wearer with the marginal portion lying in gradual waves; and a circular cord-like band at the junction of the crown and brim.

I claim:

The ornamental design for a knitted hat, as shown and described.

ELMER N. JOHA.
